UNITED STATES PATENT OFFICE.

ENDRE PAPP AND PAUL NAGY, OF NEW YORK, N. Y.

AUTO WIND-SHIELD.

1,301,308.

Specification of Letters Patent. Patented Apr. 22, 1919.

Application filed May 20, 1918. Serial No. 235,518.

To all whom it may concern:

Be it known that I, ENDRE PAPP, a subject of the King of Hungary, residing at New York, county of New York, and State 5 of New York, and I, PAUL NAGY, a subject of the King of Hungary, residing at New York, county of New York, and State of New York, have invented certain new and useful Improvements in Auto Wind-Shields, 10 of which the following is a specification.

This invention relates to improvements in wind shields, and has as its special object the provision of means whereby a composite, transparent shield is provided so that 15 the operator of the vehicle may obtain a full and complete outlook, irrespective of weather condition.

A further object is to provide means whereby the upper portion of the transparent shield may be raised or lowered in a 20 convenient manner, thereby admitting air to the vehicle.

Another object is to provide means whereby the upper sections of the shield may be 25 held at any desired angle in a positive manner, the adjustment being made from the interior of the vehicle.

These and other like objects are attained by the novel construction and combination 30 of parts hereinafter described and shown in the accompanying drawings, forming a material part of this disclosure, and in which:—

Figure 1 is a side elevational view showing a conventional type of automobile, parts 35 being broken away in order to disclose the shield attachment, one of the sections of which is in an open position.

Fig. 2 is a similar side elevational view of the same, showing both of the upper sections 40 of the shield in a raised position.

Fig. 3 is an enlarged fragmentary side view, showing the application of the device.

Fig. 4 is a horizontal sectional view, taken on line 4—4 of Fig. 3.

Fig. 5 is a further enlarged fragmentary sectional view showing the operative parts employed.

Fig. 6 is a fragmentary sectional view taken through the operating means, and

Fig. 7 is a transverse sectional view of the same.

Engaged at the front of the vehicle 10, here indicated to be of a conventional type of construction, between the overhanging roof 55 11, and the dash-board 12, is a diagonally

disposed frame 14, and extending across from side to side, at its lower portion, is a fixed transparent plate 15 which may be of the usual type of construction.

Engaged, by hinged connections 17, is an 60 upper transparent plate 18, adapted, when in a closed or lowered position, to completely fill the space between the roof and the upper edge of the fixed plate 15. A third or cover plate 20 is also secured by 65 the hinged connection 17, and adapted, when in a lowered position, to fold over and extend slightly beyond the joint between the plates 15 and 18, thus in combination with the side pane or plate 21, the front edge of 70 which is engaged with the frame 14, forming a complete covering for the vehicle front.

Extending rearwardly into the vehicle and firmly engaged with the side frames 14, 75 are brackets 24 from which extend rearwardly projecting lugs 25 and 26, the former having narrow raised projections 27 upon its upper surface and containing a screw-threaded opening 28 receptive of a 80 screw 29, the shank 30 of which extends outwardly and is furnished with a knurled operating knob or head 31.

Engaged below the upper lug 25 is a 85 spring plate 33 through which is formed a transverse groove 34, acting as a weakening cut, the plate being attached to the lug 25 by the screws 35. A hollow cap 38 surrounds the projections 25 and 26, the cap having two open slots 40 and 41, and formed 90 with an extending upper wall 42, engageable with the lugs or projections 27 so as to be normally maintained in place upon the bracket, the upper end of the cap terminating in an externally screw-threaded stem 44, 95 bored to receive the shank 30 of the screw 29.

Engageable upon the stem 44 is a knurled nut or knob 45 provided with a flanged base 46, the arrangement being such that the cap can be moved longitudinally of the bracket 100 24, the flanged base being contactable with the projections 27.

Attached to the inner surface, at the margins of the transparent plates 18, are brackets 48, having extending shanks 49, secured 105 to curved bars 50 which pass below the spring plate 33 in contact with the lower extending lug 26. These curved bars extend outward through the slot 40 in the cap 38, and may obviously be clamped in an ad- 110

justed position by manipulating the knurled head 31, the point of the screw pressing against the spring plate, forcing the bar 50 against the projection 26.

5 Similarly, the outer transparent plate 20 has secured to it brackets 52 having extending arms 53, pivotally engaged by the screws 54, with other arcuately bent bars 55 which pass below the brackets 26 and are engaged 10 by the inturned flanged element 56 of the cap 38, so that when the knob 45 is manipulated, the cap element 56 is forced firmly against the outer surface of the bar 55, clamping it against the projection 26.

15 From the foregoing, it will be seen that either the inner or outer transparent plates 18 or 20 may be raised or lowered and positively clamped in position, the movement of the bent bars being limited by projections 57 20 and 58, extending respectively from the ends of the bars 50 and 55. Thus when it is desired to provide ventilation, both of the upper transparent plates or covers may be raised and clamped in a desired adjustment 25 by manipulating the knobs 31 and 45, or in case of a storm, the inner plate 18 may be maintained in a closed position, while the upper, outer plate 20 can be clamped in angular adjustment so as to divert rain, snow, 30 etc., from striking the inner plate, each of the plates being independently operable by proper manipulation of the extending knobs.

Having thus described our invention what

we claim as new and desire to secure by Letters Patent, is.

In a wind shield, the combination with a rigid frame, a transparent plate formed in two sections contained therein, the lower section being firmly engaged in said frame, the upper section being hingedly engaged at the 40 top of said frame, a transparent outer cover plate also hingedly engaged at the upper portion of said frame, brackets secured upon the side elements of said frame, bent bars secured at their ends to said outer plates and 45 passing through said brackets, lugs projecting rearwardly from said brackets, a hollow cap surrounding said lugs, and having two open slots, an inturned flanged element on 50 said cap, and an extending screw threaded stem on said cap, a knurled knob on said stem provided with a flanged base for securing said bars in adjustment, another pair of bent bars secured to the upper section of said transparent plate, said bars passing through 55 brackets on said transparent plates, and through the slots in said cap, and a stem provided with a knurled head passing through said first named stem for clamping said last named bars in adjustment in said 60 brackets.

In testimony whereof we have affixed our signatures.

ENDRE PAPP.
PAUL NAGY.
